UNITED STATES PATENT OFFICE.

FRANK M. ASHLEY, OF NEW YORK, N. Y.

INKSTAND.

1,113,285.

Specification of Letters Patent.

Patented Oct. 13, 1914.

Application filed January 3, 1913. Serial No. 739,947.

To all whom it may concern:

Be it known that I, FRANK M. ASHLEY, a citizen of the United States, and a resident of New York city, borough of Brooklyn, in 5 the county of Kings and State of New York, have invented certain new and useful Improvements in Inkstands, of which the following is a specification.

This invention relates to inkstands, more 10 particularly to inkstands of the type wherein two separate reservoirs containing ink are formed in the same base.

The principal object of the present invention is to provide an inkstand of the above 15 character in which either reservoir may be opened for the insertion of a pen by the movement of a single element constituting the cover for both reservoirs, so that when one of the reservoirs is open the other is 20 closed and that only a small portion of the reservoir constituting a dip chamber is exposed when the reservoir is so opened.

Further objects will appear from the detailed description and will be particularly 25 pointed out in the claims.

Referring to the drawings illustrating the preferred embodiments of this invention Figure 1 is a plan view of one form in which the invention may be carried out. Fig. 2 is 30 a section taken along line 2—2 of Fig. 1. Fig. 3 is a plan view illustrating another form. Fig. 4 is a plan view illustrating still another form in which my invention may be carried out, and Fig. 5 is a section taken 35 along line 5—5 of Fig. 4.

Referring to the form of construction illustrated in Figs. 1 and 2, the base 1 has the two reservoirs formed therein and located side by side with a dividing wall 3 between them and dip chambers 4 communicate 40 with the main reservoirs and are located adjacent to one another at either side of the wall 3. Projections or tongues 5 separate the greater portion of the width of the dip 45 chambers from the reservoirs leaving narrow openings 6 through which the ink may freely pass from the main reservoirs. The cover 7 is preferably formed with guiding lugs 8 and 80 which project into the main 50 reservoirs and contact with the inner longitudinal walls thereof so as to guide the cover in a direction such as to pass from one of the reservoirs on to the other. The lugs 80 are extended so as to cover the major portion 55 of the openings 6 when the cover is shoved over to open one or the other of the

ink dips. This prevents the air from getting into the reservoirs and thus reduces the evaporation of the ink. A lateral projection 9 extends from the cover substantially from the mid-length thereof over the dip openings 4 so as to close both of these openings when the cover is in central position.

When the cover is moved into the position indicated in broken lines in Fig. 1, the dip opening 4 to the right is opened while the dip opening to the left is maintained closed. The cover is of sufficient length so as to close the reservoirs at all times no matter what the position of the cover may be as shoved to open or close the ink dips. The lugs 8 constitute stops to limit the movement of the cover and thus when the latter is moved sufficiently to open one of the dips, it is brought to a stop by the contact of the lugs 8 with one or the other of the interior walls of the reservoirs.

In the form illustrated in Fig. 3, the cover 7 instead of having the single projection at mid-length thereof, is formed of 80 sufficient width to cover the dip openings, and is reduced at its mid-length to form a recess 9^a which registers with one or the other of the dip openings or chambers 4 when the cover is shoved 85 into position to open one or the other of these. When the cover is in central position, the reduced portion 9^a is located over an enlargement 30 extending from the wall 3^a formed in line with the dip chambers 4. 90 The portions of the cover between the recess or reduced portion 9^a and the ends thereof may be considered as enlarged projections for maintaining the ink dips closed when the stand is not being used. In both of these 95 forms of construction above described, projections 10 may be formed on the top of the cover for holding a pen as shown in Fig. 3.

Referring now to the form illustrated in Figs. 4 and 5, the reservoirs 2 in the base 1 have the dip chambers 4^b on the farther sides thereof in the direction of the length of the base instead of in a lateral direction as in the forms previously described. Tongues 5^b, leaving narrow openings 6^b between the reservoirs and the dip chambers, extend from one of the reservoir walls, substantially as in the forms previously described. In this construction, the cover 7^b may be formed without any projections or 110 reduced portions as the ends thereof normally cover the dip chambers. The guiding

lugs 8^b are formed on either side to contact with the inner walls of the reservoirs substantially like the lugs 8 in the other forms described.

5 When the reservoirs are used for holding inks of different colors, small spots 11 and 12 in colors corresponding to the colors of the inks may be formed on the exterior of the cover adjacent to the respective reservoirs and thus indicate to the user in which direction to move the cover so as to open the reservoir containing the required ink. (Fig. 4.)

If it is desired, the base may be extended 15 so as to form a plurality of receptacles 13 which may be used to hold pen points, erasers, paper fasteners, etc. The walls of these receptacles may be formed with depressions 14 suitable for holding pens, etc.

20 It will thus be seen that I have provided an inkstand containing a plurality of reservoirs with a single cover therefor, which cover extends over all of the reservoirs at all times and opens one ink dip at a time, 25 so that the loss of ink due to evaporation is reduced to a minimum. Moreover, in the form illustrated in Figs. 4 and 5, this construction requires a minimum amount of material used in constructing the stand and 30 is thus efficient from the standpoint of manufacture as well as from that of use.

In all of the forms illustrated, the base is made sufficiently long so as to support the cover at all points during its entire range 35 of movement. It will be noted, however, that in the form illustrated in Figs. 4 and 5, the amount of material necessary to be put in the base is reduced by reason of the disposition of the dip chambers in alignment with the reservoirs. With this arrangement of dip chambers, the material used in the base laterally of the reservoirs for the purpose of having the dip chambers formed therein, may be dispensed with. 40 45 This saving of material may be used for forming receptacles or trays such as illustrated in Figs. 4 and 5.

Having thus described my invention, I claim as new:

50 1. An inkstand having a base portion containing a plurality of reservoirs therein located in substantial alignment with each other, an ink dip formed for each reservoir

extending at one side thereof, and a single cover for maintaining the main reservoirs 55 closed at all times, said cover having a portion thereof for closing each ink dip, said cover being movable in the direction of the longitudinal disposition of the reservoirs to uncover one ink dip at a time while maintaining all of the reservoirs closed at all times.

2. An inkstand having a base portion containing a plurality of reservoirs therein and ink dips therefor located in substantial 60 alignment with each other, and a single cover for maintaining the main reservoirs closed at all times, guiding means for the cover, said cover having a portion thereof for closing each ink dip, said cover being 65 movable to uncover one ink dip at a time while maintaining all of the reservoirs closed at all times.

3. An inkstand comprising a base portion having two reservoirs therein, an ink dip 75 for each reservoir located in alignment with said reservoirs, and a cover for closing the reservoirs adapted to open and close the ink dips, the ends of said cover extending over said dips and the intermediate portion 80 of the cover extending over said reservoirs, guiding means for the cover comprising projections extending therefrom engaging with the base, said cover being movable longitudinally to cover and uncover the ink dips 85 while maintaining the reservoirs covered at all times.

4. An inkstand comprising a base having two reservoirs therein located side by side, an ink dip for each reservoir consisting of 90 a chamber extending exteriorly thereof, and a constricted opening between said chambers and reservoir, said ink dips and reservoirs being all located in substantial alignment, and a single cover for the base, the 95 ends of which serve to open and close said ink dips, the reservoirs being closed by the body of the cover at all times.

Signed at New York city, in the county of New York and State of New York, this 100 18th day of November A. D. 1912.

FRANK M. ASHLEY.
